UNITED STATES PATENT OFFICE

93,612

DESIGN FOR A SHOE

Samuel Fradkin, Lewiston, Maine

Application July 13, 1934, Serial No. 52,579

Term of patent 3½ years

To all whom it may concern:

Be it known, that I, SAMUEL FRADKIN, a citizen of the United States, and a resident of Lewiston, in the county of Androscoggin and State of Maine, have invented a new, original, and ornamental Design for Shoes, of which the following is a specification, reference being had to the accompanying drawing, forming part thereof.

I claim:

The ornamental design for a shoe, as shown.

SAMUEL FRADKIN.
